UNITED STATES PATENT OFFICE.

JOHN BYRON GOLDSBOROUGH, OF CROTON, NEW YORK, ASSIGNOR TO THE UNDERPINNING COMPANY, OF NEW YORK, N. Y., A CORPORATION OF NEW YORK.

APPARATUS FOR THE CONSTRUCTION OF SUPPORTS FOR BUILDINGS AND OTHER STRUCTURES.

979,174.

Specification of Letters Patent. Patented Dec. 27, 1910.

Original application filed March 19, 1909, Serial No. 484,499. Divided and this application filed April 9, 1910. Serial No. 554,419.

To all whom it may concern:

Be it known that I, JOHN BYRON GOLDSBOROUGH, a citizen of the United States, residing at Croton, in the county of Westchester and State of New York, have invented certain new and useful Improvements in Apparatus for the Construction of Supports for Buildings and other Structures, of which the following is a full, clear, and 10 exact specification.

This invention relates generally to the construction of supports for buildings, building walls, and other structures, particularly to that type of such supports wherein hollow foundation elements are employed to support such structures, and it will be found to be available in connection with the method of sinking such foundation elements set out in the Breuchaud Patent No. 563,130, 20 dated June 30, 1896. It may also be employed in connection with hollow foundation elements, whether sunk by the Breuchaud method or not. It may also be employed in connection with such hollow 25 foundation elements, whether sunk under an existing wall to support the same, or sunk preliminary to the erection of any structure as a foundation for a new structure.

My invention is therefore equally available for use in connection with a new support or foundation for an already-erected structure, or for use in connection with a support or foundation upon which a new structure is to be erected.

The invention has for its object to provide an apparatus whereby the footing and consequently the supporting power of such hollow foundation elements may be increased, whether the same be deep or shallow, and 35 thereby to enable a smaller foundation element to be sunk, which will take less time and cause less friction and expense than if a large foundation element were sunk, and to give it the bearing or supporting power 40 of such larger element; further, that I am enabled to obtain all the advantages of a deep foundation without the loss of time and expense usually incident to such foundation.

A further object is to enable the bearing or supporting power of foundation elements to be made substantially uniform, whether

they are the same or of different diameters in cross-section, and whether they are sunk to the same depth or to different depths, 55 and whether they are equally or unequally loaded, and thereby I accomplish the important advantage that the resistance of the foundation to settlement, etc., is equalized, and in case of a settlement of the foundation, all parts thereof will settle equally and liability to injury thereby be avoided; 60 whereas, were the resistance of the foundation to settling unequal, the walls would be cracked and possibly the structure demolished.

A further object of my invention is that it enables me to provide a sufficient foundation for a building, no matter how heavy, without the necessity of going to bed-rock 70 or hard-pan.

A further object of my present invention is that it enables me to increase the supporting power of a hollow foundation element, 75 without increasing its size, by means located at desired points throughout the length of such foundation, whereby I am enabled to take full advantage of any strata having substantial bearing power through which such foundation may pass and am not 80 compelled to depend upon the base thereof for support.

The invention forming the subject-matter of my present application is a division of my former application, Serial No. 484,499, 85 filed March 19, 1909.

By the term "hollow foundation element," I intend to include all such hollow foundations as may be located in the earth, whether round or square, or of other shape 90 in cross-section, and whether the said foundation element, in itself, is the sole support, or whether it is strengthened by a filling of concrete, cement, brick, etc., and whether such element be styled cylinders, columns, 95 caissons, or other name be applied thereto, and whether the same be sectional or integral.

These and other objects which will appear as the description proceeds, I attain by 100 the method hereinafter described, and by the use of the apparatus illustrated in the accompanying drawings wherein—

Figure 1 is a sectional elevation of a hol-

low foundation illustrating my extended supports projecting laterally into the soil from between adjacent sections of said foundation, which is here represented as a rectangular caisson partly filled with concrete. Fig. 2 is a cross-section on the line 2—2 of Fig. 1. Fig. 3 is a view corresponding to Fig. 1, illustrating my invention applied to a hollow foundation element in the form of a sectional cylinder, the extended footings projecting laterally from between adjacent sections. Fig. 4 is a plan view of Fig. 3. Fig. 5 is a similar view to Fig. 3, illustrating the manner of arranging the plates in a cylinder to cover a greater area. Fig. 6 is a section on the line 6—6 of Fig. 5. Fig. 7 is a detail view of a closure for the slots in the cylinder employed in Fig. 5. Fig. 8 is another detail of the extended footing of Fig. 6, separately. Fig. 9 is a view similar to Fig. 1, illustrating a modified form of extended footing; and Fig. 10 is a top view of Fig. 9, parts being omitted.

The particular form of foundation element is not important to my present invention, save in so far as that it is most convenient to apply my extended footings in connection with a hollow column or caisson. Nor is my present invention limited by the manner of constructing such foundation element, etc. The same may be sunk sectionally by the resistance furnished by the weight of the already-erected wall, as in the said Breuchaud patent, or they may be sunk in the usual manner of constructing foundation caissons by the use of added weights.

The pneumatic process may be employed where advisable in sinking such foundation elements, or a water-jet may be used. Where my apparatus is employed in connection with the Breuchaud patented method, it makes a valuable adjunct to that method, for it permits a foundation element to be sunk of the smallest cross-sectional area requisite to support the compression load, and I increase the footing to any extent necessary to furnish a safe support for such foundation, without carrying the same down to bed-rock. For instance, we will assume that the load to be borne by such foundation element would be one hundred tons. Assuming that this foundation were to be driven to bed-rock, it need only have sufficient material in cross-section to support the load. As bed-rock is frequently met with only at a great depth, it is very expensive and tedious to be compelled to drive the foundation so far. If, however, the foundation elements stop short of bed-rock, for instance, in sand, they must then have a supporting power which is increased as the sand is diminished in bearing power; e. g., in the case supposed, if sand were allowed to carry a load of four tons to the square foot, a supporting power equal to

that furnished by a foundation of twenty-five square feet would be required. It would probably be impossible to sink a foundation of this size by the resistance of the wall to a safe depth. But by my invention the foundation need be no larger than required to furnish the needed strength, and the supporting power can be increased as required, and therefore a much smaller foundation may be employed, and it may safely be stopped at a point above the bed-rock where the same is at a great depth. My extended supporting-plates may be used in cases where it is not feasible to excavate below the footing; for instance, in wet soil, as quicksand, which, nevertheless, has considerable supporting power when confined so that it may not flow freely.

Broadly my invention consists in the employment of extended and extensible footings which are inserted in place after the supporting foundation is sunk and which are placed at an intermediate point in the length thereof.

In the accompanying drawings the hollow foundation element 1, is illustrated in Figs. 1, 2, 9, and 10, as a rectangular caisson, and in Figs. 3, 4, 5, and 6, as a cylinder. In each case it is composed of superposed sections in the usual way.

The extended supporting-plates 2, are inserted in place between adjacent sections of the hollow foundation elements after they are sunk, and to provide space between such sections while they are being sunk for the later reception of such supporting-plates, it may be desirable that the usual packing employed between adjacent sections should be of sufficient thickness so that when removed it will provide space for the supporting-plates when the foundation is sunk to a proper depth; or if the hollow foundation element is not sectional but integral, the supporting-plates may be inserted to place through slots formed in the sides thereof. The said supporting-plates being located in position, are forced laterally into the soil from within the hollow foundation. The method whereby this is accomplished forms part of the invention of my said application Serial No. 484,499. It may conveniently be accomplished by means of a jack, which employs the caisson as a buttress and forces the supporting-plate into the soil. Stirrups may be employed, owing to the limited space, to connect the jack and supporting-plate and permit their overlapping. The said supporting-plates having been extended sufficiently into the soil, are secured at their inner ends, as shown in Figs. 1, 2, 3, 4, 5, and 6, by being bolted between the inwardly-projecting flanges 3, 4, on adjacent sections. Owing to the great vertical pressure on the said supporting-plates, it is preferable to brace them and provide support for their

outer ends in some way, and I have illustrated several ways in which this may be accomplished. Thus in Fig. 1 are illustrated the employment of braces 5, 6, which are projected diagonally through the walls of the foundation 1, and engage at their outer ends in slots 7, formed in the upper surface of the supporting-plate 2. The side-pipes may be perforated as shown, as a convenient way of introducing grout, if desired, around the plate 2, so as to consolidate and strengthen the soil, but this is not essential. The inner end of brace 5, has an enlarged head, which is embedded in the concrete filling 9, of the foundation element, where the same is so filled, which effectually secures the said brace and extended supporting-plate against movement relative to the foundation. The brace 6, is longer and has its inner end held securely by a block 10, fixed against movement in the foundation. The said braces 5 and 6, are shown in one structure for convenience, but need not be employed together.

In Figs. 3, 4, 5, and 6, the supporting-plate 2, is formed with a web 11, which is at right angles thereto, and is preferably formed integral therewith and extends substantially to its outer edge. This provides a brace for the supporting-plate of great strength and rigidity. Its employment requires an opening, as slots 12, in the wall of the hollow foundation element for the reception of the web, and, if desired, as for instance, when sinking the foundation element through water-bearing-strata, the opening may be sealed by a suitable closure, as for instance, a sliding annular member 13, which will cover the slots when lowered as in Fig. 7, and will disclose them when raised.

In Figs. 3 and 4, I have illustrated a manner of securing the said web-brace 11, as by the use of L brackets 14, which are located one at each side of the inner end of said web and are secured thereto by bolts passing through the three plates, and which brackets are then bolted to the inner surface of the foundation element.

In cases where the foundation element is to be filled with concrete or similar filling, I may employ an inner bearing-plate 15, which is secured to the said web, preferably by being integral therewith, and which rests against the inner wall of the foundation element and is therefore shaped to fit the same, being flat for a rectangular foundation and curved (as in Fig. 8), for a cylindrical foundation. This bearing-plate, as shown in said figure, is formed with a space between it and the supporting-plate 2, for the reception of the flange 3. This space, however, is unnecessary if no flange is employed. The said bearing-plate 15, and web 11, will effectually seal the slot 12, and the bearing-plate will engage against the concrete filling and ef-

fectually support the web and hold the plate 2, against movement relative to the foundation.

Figs. 5 and 6 also illustrate the employment of the supporting-plates 2, without the web and bearing-plate, in the same form shown in Fig. 1, and to distinguish these from the other supporting-plates in Fig. 6, I will letter one of them 2^A. They are, however, the same kind of supporting-plates, the only difference being in the manner of bracing. Plates 2^A, are useful in connection with cylindrical foundations, one such being shown in Fig. 6, and are forced into the soil beneath adjacent bearing-plates 2, and are for the purpose of closing the spaces between the outer parts thereof and thereby of increasing the supporting surface. They are braced by the superposed portions of the adjacent plates and their inner ends lie between the flanges 3 and 4, and below the supporting-plates 2, and are secured by the bolts that unite those parts.

In Figs. 9 and 10, is illustrated a modified form of extended supporting-plate, consisting of a curved-plate 16, which is inserted in a curved-slot 17, formed between adjacent sections of the hollow foundation element or in the wall thereof, and driven out by a jack 18, acting against resistance of a block 19, situated under flanges 20, and pressing downward on a block 21, and thereby forcing plate 16 out. This plate 16, may be maintained in position while it is being driven by blocks 22, 23. After the plate 16, is driven to position, it may be braced by pipe-braces 24, perforated for grouting purposes, which are inserted through openings in the wall of the foundation element, and afterward secured in position by plates or caps 25, screwed to the said walls. The plates 11, have heads 20, to prevent their passing out the curved slot in the walls, also to brace the same and support them when the hollow foundation is filled with concrete.

The construction illustrated in Figs. 9 and 10 may be advantageously employed in some cases in inverted position; that is, so that the curved-plates 16, hook into the earth as a parachute hooks into the air. By the use of this curved-plate a longer plate can be placed in position than would be possible if a straight plate were used. This form of my invention, when used in the arrangement of Figs. 9 and 10, may be as useful for the underpinning and securing of tunnels, both subterranean and sub-aqueous, as it is to the support of buildings, and I intend to include such tunnels in the term "other structures" in the claims. It is known that such tunnels, when driven below rivers, frequently through necessity are driven through unstable soil but ill-adapted to support a tunnel structure and maintain it in stable condition, and that such tunnel structures,

while they may need support to prevent sinking, also frequently need support to prevent their rising. In the latter case the foundation elements, or as they may then be more properly termed, "anchors," need only be sunk a sufficient depth to secure firm material, and for this use the construction illustrated in Figs. 3, 5, and 9, and other figures may be employed. In case Fig. 9 is employed, it may be inverted, in which case the braces 24, should be screw-threaded at their outer ends and tapped into the extended footings 16, to resist a pulling rather than a pushing strain. The great advantage of this foundation is that by its use buildings may be supported upon a smaller foundation and the supporting-plates may be extended into the soil between any desired number of sections or at any desired place, so that each foundation element may have its supporting-plates positioned at any desired location, according to soil, etc., and thereby the total supporting power of the foundation element may be greatly increased and the tendency to settling through any future disturbance of the soil minimized, owing to the fact that such disturbance will not probably affect more than one level and the supporting-plates will lie at several levels. By this means buildings of any weight may be cheaply and safely supported on what would otherwise be unstable material, or where the character of the soil is such that the cost of securing a foundation by the present methods of open excavation or caissons is prohibitive. Desirable building sites are rendered unavailable owing to the high costs by present methods of building foundations to rock or to a considerable depth in or through material of an unstable character, and the method herein described is intended to overcome these obstacles.

An advantage of my invention is that the forcing out of the extended footings tends to compress and consolidate the soil through and into which they are forced, thereby increasing the bearing power of the soil and decreasing its liability to permit settlement.

The foregoing presents particular embodiments of my invention, which, however, may be modified within the usual skill of the engineer without departing from the principle thereof.

What I claim and desire to secure by Letters Patent is:

1. A support, for a hollow structure composed of connected sections, comprising extensions therefrom projecting laterally into the adjoining soil or material, and secured to such structure by having their inner ends inserted between the joints of adjacent sections, and permanently and rigidly held in such position by being attached to such structure.

2. A support for a building or other

structure, comprising a hollow foundation element and extended supports therefor projected laterally into the soil from within said foundation at a point or points intermediate of the top and bottom of said foundation, and means for rigidly and permanently securing said extended supports in place.

3. A support for a building or other structure, comprising a hollow foundation element, and extended supports therefor projected laterally into the soil from within said foundation at a point or points intermediate of the top and bottom of said foundation, and braces for rigidly and permanently holding said extended supports in position.

4. A support for a building or other structure, comprising a hollow foundation element, and extended supports therefor consisting of plates projected laterally into the soil from within said foundation at a point or points intermediate of the top and bottom of said foundation, and means for rigidly and permanently holding said extended supports in place.

5. A support for a building or other structure, comprising a hollow foundation element, and extended supports therefor consisting of plates projected laterally into the soil from within said foundation at a point or points intermediate of the top and bottom of said foundation, and braces for rigidly and permanently holding said plates in position, engaging said plates outside the foundation, and anchorages for said braces at their inner ends.

6. A support for a building or other structure, comprising a hollow foundation element composed of superimposed sections, extended supports therefor projecting laterally into the adjacent soil or material from within such foundation and between such sections, and means for rigidly and permanently bracing such extended supports in position.

7. A support for a building or other structure, comprising a hollow foundation element composed of superimposed sections, extended supports therefor projecting laterally into the adjacent soil or material from within such foundation and between such sections, and braces for rigidly and permanently holding such extended supports in position.

8. A support for a building or other structure, comprising a hollow foundation element composed of superimposed sections, extended supports therefor comprising plates extending laterally into the adjacent soil or material from within such foundation and having their inner ends connected between the joints of adjacent sections, and means for rigidly and permanently bracing said plates in position.

9. A support for a building or other structure, comprising a hollow foundation element composed of superimposed sections, extended supports therefor comprising plates extending laterally into the adjacent soil or material from within such foundation and having their inner ends connected between the joints of adjacent sections, and braces for rigidly and permanently holding said plates against displacement relative to said foundation engaging said plates outside the foundation, and anchorages for said braces at their inner ends.
10. A support for a building or other structure, comprising a hollow foundation element, and extended supports therefor comprising a curved-plate projected laterally into the soil or material from within said foundation at a point or points intermediate the top and bottom thereof, and
- means for rigidly and permanently bracing said plate in position.
11. A support for a building or other structure, comprising a hollow foundation element and extended supports therefor, comprising a curved-plate projected laterally into the soil or material from within said foundation at a point or points intermediate the top and bottom thereof, and a brace for permanently and rigidly holding said plate in position, and anchorages for said brace in said plate and said foundation element.
- In witness whereof I have hereunto set my hand in the presence of two subscribing witnesses.
